UNITED STATES PATENT OFFICE.

CHARLES EDWARD ITSKIN, OF LOUISVILLE, KENTUCKY.

PEN AND PENCIL CASE.

Application filed July 28, 1924. Serial No. 728,703.

To all whom it may concern:

Be it known that I, CHARLES E. ITSKIN, a citizen of the United States, residing at Louisville, in the county of Jefferson and State of Kentucky, have invented certain new and useful Improvements in Pen and Pencil Cases, of which the following is a specification.

This invention relates to new and useful improvements in a combined pen and pencil case, and has for its principal object to provide a simple and efficient device which may be used either as a pen or a pencil, as may be desired.

Another important object of the invention is to provide a combined pen and pencil case of the above mentioned character, wherein the pencil holder is provided with means for receiving and supporting auxiliary implements, which may be readily and easily actuated, whenever it is desired to use the same.

A further object of the invention is to provide a combined pen and pencil case of the above mentioned character, which is simple in construction, inexpensive, strong and durable, and further well adapted for the purposes for which it is designated.

A still further object is to provide a pen and pencil case of the above mentioned character, which may be readily and easily carried in the pocket of a person.

Other objects and advantages of this invention will become apparent during the course of the following description.

In the accompanying drawing, forming a part of this specification, and in which like numerals designate like parts throughout the same:

Figure 1 is a longitudinal sectional view of the invention.

Figure 2 is a fragmentary side elevation showing one end of the device.

Figure 3 is a sectional view, taken approximately upon the line 3-3 of Figure 2, and

Figure 4 is a side elevation of one of the implements carried by the pencil holder, showing the means for moving the same out of the holder and further adapted to retract the implement when not in use.

In the drawing, wherein for the purpose of illustration is shown the preferred embodiment of my invention, the numeral 1 designates a cylindrical casing, which is formed of any suitable material, prefer-

ably aluminum, and the open ends thereof are internally threaded as illustrated at 2 and 3 respectively, in the drawing. Adapted to be supported in the threaded end 2 of the casing 1 is the pen holder 4, the same comprising a hollow tubular member which is closed at its respective ends with the exception of suitable openings provided in the ends for receiving the respective ends of the pen 5. A shoulder 6 is provided on the inner end of the pen 5 and engages the inner closed end of the holder 4 to prevent the outward movement of the pen with respect to the pen holder. The pen point 7 extends beyond the outer closed end of the holder 4, and a suitable cap 8 fits over the outer end of the pen holder and the pen point 7 to protect the same, when the pen is not in use.

Threaded into the opposite threaded end 3 of the casing 1 is the pencil holder 9, the same being of a suitable length.

The pencil holder 9 is hollow, and the outer end thereof is provided with a hinged connection 19, the hinged portion being shown at 20. The purpose of providing the outer end of the pencil holder 9 with the hollow portion is to provide a means for receiving an additional supply of leads 21, which are used in connection with the longitudinally extending recesses 12 provided in the outer end of the pencil 9 and the hinged section 19 in the manner as clearly illustrated in Figure 3. Each of the pencil elements 21, receivable in each recess 12, has a detachable handle 17 slidable through slot 18 associated with the inner end thereof for moving the pencil outwardly from the holder when it is desired to use the same or for retracting the lead within a recess. When the lead in the recesses has become entirely used, the ends of the lead may be removed from the handle, and a new lead inserted in place thereof. A cap 16 is receivable over the end of the pencil holder 9 so as to hold the hinged portion 19 closed and to prevent the extension of the leads 21.

The provision of a pen and pencil case of the above mentioned character enables a person to have at hand either a pen or pencil, or any other desired implement which may be carried in the pocket of a person, the same being accessible at all times. The simplicity with which my device is constructed enables the several parts to be readily assembled or removed from the casing

and when the caps are on the outer ends of the pencil holder and the pen holders there will be no danger of the pen or pencil becoming broken while being carried around by a 5 person.

A device of the above mentioned character may be manufactured at a very low cost, and will possess numerous advantages and render possible the carrying of the several implements by a person in a more compact manner. 10

While I have shown the preferred embodiment of my invention, it is to be understood that various changes in the size, shape, and 15 arrangement of parts may be resorted to, without departing from the spirit of the invention and the scope of the appended claims.

Having thus described my invention, what 20 I claim is:

1. A pencil holder of the class described including a cylindrical body adapted to hold

a pencil at one end, and having its other end hollow and formed in a pair of hinged sections, and a cap receivable over said sections 25 to hold them together.

2. A pencil holder of the class described including a cylindrical body adapted to hold a pencil at one end, and having its other end hollow and formed in a pair of hinged sections, a cap receivable over said sections to hold them together, one of said sections provided with a longitudinally extending recess, and a slot communicating with the inner end thereof, and a member slidable in 30 the recess and having an extension slidable in the slot. 35

3. A device of the class described including a pair of hinged sections forming a hollow cylinder, and a cap threadedly engaged over one end of the cylinder 40 for holding the sections together.

In testimony whereof I affix my signature.
CHARLES EDWARD ITSKIN.
